**RAMJET MOTOR WITH MULTI-STAGE
BURNING**
Frederick L. Haake, 1519 Little Farms Road,
Oxnard, Calif.
Filed June 26, 1962, Ser. No. 206,545
8 Claims. (Cl. 60—35.6)
(Granted under Title 35, U.S. Code (1952), sec. 266)

The invention described herein may be manufactured and used by or for the Government of the United States of America for governmental purposes without the payment of any royalties thereon or therefor.

This invention relates to ram jet motors, and more particularly to such motors wherein a multi-stage burning effect is produced in the combustion chamber to increase the operating efficiency and thrust of the motor.

One of the most critical problems involving ram jet motors is to obtain more complete burning of the fuel to increase the total thrust for a given amount of propellant. Whether the ram jet motor be operated on solid or liquid propellant fuels, incomplete combustion occurs whenever the fuel particles, for one of many reasons, pass through the combustion chamber without burning, or are burned outside the nozzle and thus do not contribute to the engine thrust.

One of the basic causes of incomplete combustion is the absence of proper mixing between the ram air and the propellant particles. Various means have been devised to improve such mixing, such as installation of baffle plates to increase turbulence and the like. In addition, substantial research has been conducted with regard to the cross-sectional grain configuration to control and improve burning efficiency, and to vary the speed of the ram air which provides the oxidizer to the propellant.

According to the present invention improved burning efficiency in the ram jet engine is achieved by providing therein a plurality of different size ram air passages for varying the speed of the ram air passing through the engine in a prescribed arrangement, such as to provide, in effect, multi-stage burning areas in the combustion chamber. In other words, at least one ram air passage is so dimensioned as to introduce lower velocity ram air, and at least one ram air passage has a larger dimension to introduce a higher velocity air, such that respective combustion areas or burning zones occur in generally longitudinally disposed relation within the combustion chamber. This invention is particularly suitable for use in solid propellant motors. For example, the ram jet motor can be fabricated of a plurality of uniform elongate solid propellant grains longitudinally arranged together in a bundle to provide one or more longitudinal passages formed therebetween. The bundle of grains is supported within the engine casing such that one or more passages is provided between the bundle of propellant grains and the motor casing of a different size than the one or more passages within the bundle. The slower ram air passing through the smaller air passages, being at a higher temperature, will create a combustion area immediately aft of the burning end of the propellant bundle, whereas the ram air passing through the larger passage being at a higher velocity will create a combustion area further aft in the combustion chamber, or form an extension thereof mixing and burning the unburned propellant particles passing aft from the previous combustion stage. In order that the cross-sectional area of the respective air passages remain substantially the same throughout motor burning, the longitudinal surfaces of the individual grains are restricted to insure an end-burnning grain. The aforescribed arrangement in effect

2

forms a two-stage combustion effect with additional stages possible by providing additional passages different sizes.

A propellant motor fabricated of a plurality of simply constructed propellant grains, which can be identical, provides a convenient method to build up motors of different sizes, as well as different arrangements of burning stages by creating passages of various sized and configurations. Compared to the complicated cruciforms or star grain configurations presently employed in solid propellant motors, the grains of the instant invention can be circular or non-circular in cross-section, and of the same size or differing in size depending on the desired ram air flow through the various passages, and thus materially reducing the cost and complexity of motor fabrication.

One object of this invention is to provide a ram air, reaction type motor having improved burning efficiency; and a corollary object is to obtain increased burning efficiency by varying the number and/or sizes of the ram air passages.

Another object is to provide such ram air motor having a solid propellant motor fabricated of a plurality of uniform grains which can be assembled in various configurations according to the required number and arrangement of ram air passages.

A further object is to provide a ram air motor which is constructed to provide, in effect, a plurality of longitudinally spaced combustion areas.

Still a further object is to provide a solid propellant motor that can be inexpensively constructed and which can be fabricated in various sizes.

Other objects and many of the attendant advantages of this invention will be readily appreciated as the same becomes better understood by reference to the following detailed description when considered in connection with the accompanying drawings wherein:

FIG. 1 is a diagrammatic longitudinal sectional view of a ram air missile having a reaction-type motor, using either liquid or solid propellant fuels, and employing an arrangement of different sized ram air passages according to the present invention to provide during operation respective combustion envelopes defined by broken lines;

FIG. 2 is a diagrammatic view of a solid propellant motor fabricated of a plurality of identical and irregular shaped propellant grains suitably arranged according to the teaching of the present invention to provide one central ram air passage and four outer ram air passages of larger dimensions;

FIG. 3 is a similar view as FIG. 2 wherein the propellant grains are identical but triangular in cross-sectional configuration to provide two central ram air passages and four outer ram air passages;

FIG. 4 is a similar view as FIG. 2 wherein the propellant grains are identical and cylindrical in shape, and arranged to provide a single central ram air passage and four outer ram air passages;

FIG. 5 is a diagrammatic longitudinal sectional view of a ram air missile employing a solid propellant motor of the type illustrated in FIG. 4 showing the combustion envelopes in broken lines created by the respective air passages; and

FIG. 6 is a diagrammatic sectional view of a solid propellant motor comprising a plurality of different sizes of cylindrical propellant grains arranged to provide another arrangement of ram air passages of different dimensions.

Referring to the drawing where like reference numerals refer to similar parts throughout the drawing there is shown in FIG. 1 a ram air missile 10 comprising generally a cylindrical casing 12 having a nose end provided with an air diffuser 13 forming with the casing a ram air intake 14, and an aft end provided with a nozzle 16. An end-burning propellant motor 18 is supported intermediate

the casing in spaced relation thereto by a spider 19 which allows unrestricted flow of ram air. For the general purpose of this invention, motor 18 can be of a liquid propellant type or a solid propellant type, although the concept is particularly suitable for solid grain propellant motors for reasons hereinafter described. Only one forward spider 19 is used in end-burning type of solid propellant grains to avoid interference with the burning. A combustion chamber 20 is longitudinally disposed between motor 18 and nozzle 16, the combustion chamber being so longitudinally dimensioned as to ensure adequate mixing volume for the various burning stages that are caused by the invention motor. As an example of the relative dimensions of the diameter of the casing with respect to the length of the combustion chamber, for a casing 8 inches in diameter the length of the combustion chamber should be in the order of approximately twenty inches. In combined rocket-ram jet motors, the space normally occupied by the solid propellant rocket motor is particularly suitable as the combustion chamber of the ram jet motor.

One of the basic concepts of the present invention is to provide different sizes of ram air passages 22 and 24 through motor 18 to improve the burning efficiency in the combustion chamber in the following manner. Air passage 22 may be annular in shape, or segmented as illustrated in other modifications to be described, and in any event larger than central passage 24 so that the ram air velocity in passage 22 is greater than the ram air velocity in passage 24. When motor 18 is ignited, the ram air in central passage 24 forms a central combustion envelope or stage generally defined by the broken line 26, which stage is formed in the forward portion of combustion chamber 20. Passage 22 being larger than passage 24 presents less friction to the ram air flow therethrough enabling the ram air in passage 22 to be at a higher velocity and pressure. Any unburned propellant particles from the first stage 26 will be swept further aft and mixed with oxygen by the ram air in passage 22 and ignited in the second stage generally defined by the envelope 28, which is tubular in configuration. In addition, it is also believed that hot burned propellant particles from the first stage will be forced aft into the second stage burning area where they will have an effect of still further increasing the temperature of the ram air therein to provide additional thrust. Although the first and second stages 26 and 28, respectively, are illustrated as well defined volumes, it is apparent that such a condition may not actually be so clearly defined because of turbulent air currents. Under actual operating conditions the burning stages 26 and 28 will probably not be readily distinguishable and will probably appear as one combined burning volume. The higher velocity air in passage 22 as it enters the combustion chamber will create a rolling action, represented by arrows 29, to provide good mixing of the solid propellant particles and oxygen.

It is apparent that the combustion volume caused by the second stage formed aft of the first stage burning volume will increase the total combustion volume within combustion chamber 20 to obtain maximum thrust from the motor. Obviously, the combustion chamber must be dimensioned to be capable of accommodating the enlarged combustion volume resulting from the use of the instant invention so that substantially all combustion occurs within the motor and not outside the motor where it provides no thrust component.

Although inner and outer passages 24 and 22 are illustrated as being smaller and larger in cross sectional area, respectively the arrangement can be reversed as will be hereinafter described in other embodiments of the invention.

FIG. 2 is a cross-sectional view of a solid propellant motor 30 fabricated of four identical and irregular concavo-convex shaped propellant grains 32. The longitudinal surfaces of each grain have a restrictive coating, not shown, to ensure only end burning of the propellant

rains. The grains are transversely arranged in the casing in quadrants, with the outer edges contacting the inner casing wall 34 and the inner ends abutting adjacent grains to form four large outer ram air passages 36 and one small central passage 38. The operation of motor 30 is substantially the same as previously described with motor 18 in FIG. 1. Since the solid propellant grains are of the end-burning type, the cross-sectional dimensions of passages 36 and 38 will remain substantially constant throughout ram air motor burning.

FIG. 3 is a cross-sectional view of a solid propellant motor 40 formed of six identical end-burning propellant grains 42 triangular in cross-section. The grains are arranged with the apexes of four of the grains contacting the inner casing wall 44 to form four segmental outer ram air passages 46, with the remaining two grains arranged base-to-base to form two central passages 48. Here also, the operation of motor 40 is similar to motor 18 in FIG. 1 with the exception that two central burning envelopes may be formed in the combustion chamber, one for each central passage 48, instead of one envelope as in FIG. 1.

FIGS. 4 and 5 illustrate another modification of a propellant motor 50 composed of four identical cylindrical grains 52 suitably supported in longitudinally contiguous relation within casing 54. The central longitudinal air passage 56 between the grains is larger than any one of the four outer longitudinal air passage 58 formed between adjacent pairs of grains and the inner wall of the casing. As the ram air velocity will be greater in the larger central air passage 56 than in the smaller outer air passages 58, burning stage 60 formed adjacent the central air passage 56 will extend further aft in the combustion chamber 62 and form in effect a second burning stage, whereas the burning stages 64 adjacent the outer air passages 58 form in effect first burning stages. It is apparent that if more smaller passages 58 are desired the number of grains can be increased to give the desired result, as in FIG. 6 to be described.

Still another modification of the novel motor is shown in FIG. 6 comprising a plurality of different sizes of cylindrical propellant grains, namely, an outer hollow circular array of smaller identical grains 66 supported directly in a casing 68 and forming a plurality of outer passages 72 therebetween. A plurality of larger size propellant grains 74 are secured within the circular array of smaller grains to form two inner air passages 76. One satisfactory arrangement of such a motor can consist of approximately ten outer individual grains, and two inner grains, as illustrated. If desired the circular array of grains 66 could be smaller and supported within the casing by spider, much as in FIG. 1, to form one outer annular passage instead of individual outer segmented passages 72.

The instant invention discovers the improved efficiency that can be obtained in a reaction type ram air motor when the motor is provided with a plurality of ram air passages that vary in size. The radial relation of the smaller and larger air passages may vary depending on the desired result. For example, the smaller passage can be centrally located and the larger passage outwardly arranged (FIGS. 1, 2 and 3), or in reverse order (FIGS. 4, 5 and 6). A solid propellant motor utilizing the invention is easily fabricated of small individual propellant grains which can be all uniform and simple in design as a manufacturing expedient, although grains of different sizes can be employed to give a desired result. In very large solid propellant motors the advantages of simplicity in fabrication, manufacturing and handling as readily apparent as well as obviating grain fabrication problems. The number, sizes and disposition of the individual grains will depend on the size of the motor as well as other factors. Increased burning efficiency in this type of motor is believed achieved because of the improved mixing of the propellant and the ram air. In

addition, the use of many small air passages decreases the velocity of the ram air flowing over the burning surfaces of individual propellant grains raising the air temperature. Also, the high velocity air in the larger passage mixes with the low velocity air to form in effect an after burning stage in the combustion chamber. In other words, the slower ram air passing through the ram jet motor forms a first stage burning while the faster ram air forms a second stage burning. It is apparent that the ram air motors of FIGS. 2 to 6 inclusive can be mounted within the casing, such as in FIG. 1, to provide an outer annular ram air passage.

Obviously many modifications and variations of the present invention are possible in the light of the above teachings. It is therefore to be understood that within the scope of the appended claims the invention may be practiced otherwise than as specifically described.

I claim:

1. A reaction-type ram air motor comprising
  - (a) a cylindrical motor casing terminating in a nozzle 20
  - (b) a solid propellant charge mounted in said motor casing longitudinally spaced from said nozzle to form a combustion chamber therebetween.
  - (c) said solid propellant charge being formed of a plurality of individual solid propellant grains of the end burning type the total cross-sectional area of all the grains combined being less than the cross-sectional area of the motor casing, said grains being arranged transversely in said casing to provide a plurality of longitudinal ram air passages leading to the combustion chamber; 25
  - (d) at least a portion of said air passages having different cross-sectional areas to pass ram air at different velocities; said air passages being open along their entire length throughout operation of the motor; 35
  - (e) the cross-sectional areas of said air passages remaining substantially constant throughout motor combustion
  - (f) the longitudinal length of the combustion chamber being of a dimension as to allow the formation of longitudinally disposed burning zones therein for the respective ram air passages so as to achieve substantially complete combustion in the combustion chamber prior to exhaust through said nozzle. 40
2. The ram air motor of claim 1 wherein all of said solid propellant grains are identical in shape and size. 45
3. The ram air motor of claim 1 wherein all of said solid propellant grains are non-cylindrical.
4. The ram air motor of claim 1 wherein all of said solid propellant grains are cylindrical.
5. The ram air motor of claim 1 wherein the air pas-

sages of a smaller cross-sectional area are arranged radially outwardly in the casing from the air passage having larger cross-sectional area.

5 6. The ram air motor of claim 1 wherein said solid propellant charge is supported in spaced relation to the inner wall of the motor casing to form an annular ram air passage around said charge.

10 7. The ram air motor of claim 1 wherein the individual propellant grains are cylindrical and are transversely arranged peripherally in the casing with their adjacent longitudinal surfaces abutting to each other in circular relation and engaging the inner wall of the casing, adjacent pairs of grains forming therebetween and with the casing a longitudinal air passage.

15 8. A reaction-type ram air motor comprising

- (a) a cylindrical motor casing terminating in a nozzle;
- (b) a propellant charge mounted in said motor casing longitudinally spaced from said nozzle to form a combustion chamber therebetween;
- (c) said propellant charge arranged in said casing to provide a plurality of longitudinal ram air passages leading to the combustion chamber;
- (d) at least a portion of said air passages having different cross-sectional areas to pass ram air at different velocities; said air passages being open along their entire length throughout operation of the motor;
- (e) means for maintaining constant the velocity of the air reaching said combustion chamber through the longitudinal ram air passages substantially constant throughout motor combustion;
- (f) the longitudinal length of the combustion chamber being of a dimension greater than the diameter of the casing as to allow the formation of longitudinally disposed burning zones therein for the respective ram air passages so as to achieve substantially complete combustion in the combustion chamber prior to exhaust through said nozzle.
